CARBON CONTACT

Walter M. Austin, Pittsburgh, Pa., assignor to
Westinghouse Electric & Manufacturing Com-
pany, a corporation of Pennsylvania

Application May 19, 1927, Serial No. 192,583

10 Claims. (Cl. 200—166)

My invention relates to circuit interrupters and more particularly to new carbon contacts therefor.

One object of my invention is to provide means for supporting the carbon from the retaining member without employing the usual mounting-bolt holes in the body of the carbons.

Another object of my invention is to provide a carbon that shall be mounted in a retaining sheath, which retaining sheath contains the means for mounting the carbon contact on the circuit-interrupter structure.

A further object of my invention is to provide a carbon member and a receiving sheath for the said carbon member, both of such shape and dimensions that they shall be retained in a fixed position relative to each other by a spring member.

It has been the practice in the past to support carbon contacts in position in circuit-interrupters by means of bolts passing through the carbon members themselves. This reduced the cross-section of the carbon member in the vicinity of the bolt holes so that stresses to which the said member was subjected would frequently result in the breaking of the carbon in the vicinity of the holes.

It is the object of this invention to overcome this breaking by supporting the carbon in a retaining sheath which sheath also contains the means for mounting the entire unit in position in the circuit-interrupter.

The invention will be better understood by referring to the drawing in which:

Figure 1 is a view in elevation of a circuit interrupter containing the inventor's sheathed type of carbon contactor;

Fig. 2 is a view in elevation showing a front view of the carbon supported in the sheath above-described;

Fig. 3 is a similar view taken at 90° from Fig. 2; and

Fig. 4 is a bottom view of the structure shown in Figs. 2 and 3.

My invention comprises, in general, a circuit breaker 1 mounted on a panel 2 having contact members 3 and 4 that are bridged by the conducting member 5. The supporting frame 6 is mounted on the panel 2 and contains the operating mechanism 7 and the overload and tripping mechanism 8. The bridging member 5 has cooperating with it the secondary copper contact 9 and the tertiary or carbon contact 11.

The carbon contact 11 is constituted by the carbon member 12 that is contained within the supporting sheath 13 and retained in position by the

spring member 14 that is riveted to the retaining sheath 13 by rivets 15. The body portion of the supporting sheath 13 is constructed from a thin sheet material containing punched and drawn holes 16 which support the mounting screws 17 flush with the inner face of the supporting sheath 13.

The front and rear faces, and also the top and bottom faces, of the carbon 12 are in parallel relation respectively to each other; but the sides 18 and 19 are inclined to the bottom and rear face, converging toward the top and front face respectively. This construction constitutes a wedge both in the upward and outward direction.

The supporting sheath 13 comprises a body 70 portion and two side members 21 and 22 which form a wedge shaped sheath, the sides 21 and 22 bearing the same inclination to each other as the sides 18 and 19 of the carbon member 12. The sheath 13 thus rigidly retains the carbon 12 when the latter is pushed upward therein by the spring member 14.

In manufacturing my carbon contact, the portion of the carbon member 12 which is to make contact with the supporting sheath 13 is first 80 copper plated and then tinned before assembly. The inner surface of the two sides 21 and 22 and the body portion of the supporting sheath 13 are tinned as are also the heads of the supporting screws 17. After the carbon 12, the supporting screws 17, supporting sheath 13 and the biasing spring member 14 have all been assembled, the entire member is heated to a suitable temperature to sweat the members together and so unite them into a single unit.

It will thus be seen that I have provided a carbon contact that may be supported in a circuit interrupter or other device without the necessity of weakening the structure by the use of such holes through the carbons as have heretofore been employed as a mounting means. I have also provided a spring member to retain the carbon in the supporting sheath in fixed relation thereto, even though the solder or the copper plating should be loosened by repeated 100 operation.

Although I have described a specific embodiment of my invention, it is obvious to those skilled in the art that various modifications may be made without departing from the principles set forth in the appended claims.

I claim as my invention:

1. A carbon member of truncated wedge shape the sides of which diverge toward the bottom and rear face, a metal sheath member having a body 110

portion and two side members, the said side members being in diverging relation to each other corresponding to the relation of the sides of the carbon, and means for biasing the carbon into firm relation with the sheath member.

2. A carbon member having a pair of opposite sides inclined out of a perpendicular to the planes of the bottom and rear faces converging toward the top and front faces, the rear face and a portion of the aforesaid opposite sides being copper plated and tinned and a metal wedge shaped member having sides sloping in the above said manner for receiving the carbon, the inner side of the said receiving member being tinned and sweated to the carbon.

3. A carbon member having a pair of opposite sides inclined out of a perpendicular to the planes of the bottom and rear faces converging toward the top and front faces, the rear face and a portion of the aforesaid opposite sides being copper plated and tinned, a metal wedge-shaped member the sides of which are inclined to receive the carbon, the inner side of the said receiving member being tinned and sweated to the carbon and a spring member for retaining the carbon member in firm relation with the receiving member if the sweated portion become loosened.

4. A carbon member having a pair of opposite sides inclined out of a perpendicular to the planes of the bottom and rear faces converging toward the top and front faces, the rear face and a portion of the aforesaid opposite sides being copper plated and tinned, a metal wedge-shaped member having its sides sloping inward and upward for receiving the carbon, the inner side of the said receiving member being tinned and sweated to the carbon and mounting means cooperating with the retaining member for supporting the assembled unit.

5. A carbon member having a pair of its opposite sides inclined out of a perpendicular to the plane of the bottom and rear faces, a receiving member comprising a body portion and two side portions, the said side portions being inclined in substantially the same manner as the aforesaid sides of the carbon, and a spring member pressing on the bottom of the carbon adapted to force the carbon into firm engagement with the receiver.

6. A carbon member having a pair of its opposite sides inclined out of a perpendicular to the plane of the bottom and rear faces, a receiving member comprising a body portion and two side portions, the said side portions being inclined in substantially the same manner as the aforesaid sides of the carbon, a spring member pressing on the bottom of the carbon adapted to force the carbon into firm engagement with the

receiver, and mounting screws in the body portion of the receiver having the heads thereof flush with the inner face of its body portion and held in this position by the carbon.

7. A carbon contact comprising a carbon member having a contact or front face, a rear face opposite thereto, and two opposite side faces, a supporting member for the carbon member having a body portion engaging the rear face and two side portions engaging the side faces of the carbon member, said side faces and side portions converging in a direction generally parallel to the front face, and means acting against the carbon member in the direction of convergence of said side faces to wedge the same between the side portions of the supporting member.

8. A carbon contact comprising a carbon member having a contact or front face, a rear face opposite thereto, and two opposite side faces, a supporting member for the carbon member having a body portion engaging the rear face and two side portions engaging the side faces of the carbon member, said side faces and side portions converging in a direction generally parallel to the front face, means acting against the carbon member in the direction of convergence of said side faces to wedge the same between the side portions of the supporting member, and means for retaining the carbon member against forward movement relative to the supporting member.

9. A carbon contact comprising a carbon member having a contact or front face and a rear face opposite thereto, a supporting member for the carbon member having a body portion engaging the rear face and two side portions engaging the opposite sides of the carbon member, said side portions being so disposed that the carbon member is wedged in the supporting member when moved in a direction generally parallel to said front face, and means acting against said carbon member in said direction to retain the same in wedged engagement.

10. A carbon contact comprising a carbon member having a contact or front face, a rear face opposite thereto and two opposite side faces, a supporting member for the carbon member having an intermediate portion engaging the rear face and two side portions engaging the side faces of the carbon member, said side faces and side portions converging from the rear face toward the contact face and also converging in a direction generally parallel to the contact face, and means acting against the carbon member in the direction of said last-mentioned convergence of said side faces to wedge the same between the side portions of the supporting member.
